UNITED STATES PATENT OFFICE.

GEORGE POMINVILLE, OF ST. HYACINTHE, QUEBEC, CANADA.

ELECTRIC WATER HEATER.

Application filed September 1, 1920. Serial No. 407,292.

To all whom it may concern:

Be it known that I, GEORGE POMINVILLE, a subject of the King of Great Britain, residing at St. Hyacinthe, in the Province of Quebec, Canada, have invented certain new and useful Improvements in Electric Water Heaters; and I do hereby declare that the following is a full, clear, and exact description of the invention, such as will enable 10 others skilled in the art to which it appertains to make and use the same.

The present invention relates to electric heaters and more particularly to a heater of this character which may be used in connection with hot water heating systems. An object of the present invention is to produce an electric heater which may be easily and readily applied within the hot water system, or which may be applied to the 20 individual radiators having water therein to be heated.

A further object of the invention is to provide a device adapted for connection to any type of domestic or commercial water 25 reservoirs or tanks, and which is capable of relatively instantaneously heating the water in the reservoir.

With the above and other objects in view which will hereinafter appear as the description continues, the invention consists of the novel features of construction, combination and formation of parts as will be herein-after more fully described and particularly pointed out in the appended claim.

35 In the accompanying drawings:—

Figure 1 is an elevational view of a water tank, illustrating the application of my invention thereto;

Figure 2 is a magnified view of the device 40 vice detached from the tank;

Figure 3 is a horizontal section of the device;

Figure 4 is a plan view of the inner surface of the resistance holding plate and 45 outer cover plate; with the circuit wires schematically illustrated; and,

Figure 5 is an end elevational view of the same.

This invention will be best understood 50 from a consideration of the following detailed description wherein like and corresponding parts are designated by similar reference characters throughout the several views.

55 The numeral 1 designates the reservoir or tank of any desirable construction, which

is connected to the water supply pipe 2, by the pipe 3 and three way fitting 4. Likewise a pipe 5 leads from the top of said reservoir 1 and is connected by the elbow 60 fitting 6 to an outlet pipe 7. A pipe 8 is connected to one branch of the three way fitting 4 and carries on its opposite end the three way fitting 9. A similar three way fitting 10 is connected to the outlet 65 pipe 7.

Two vertical pipes 11 and 12 have their lower and upper ends connected to fittings 9 and 10 respectively, and at their inner ends these pipes 11 and 12 take into interiorly threaded openings in the enlargements 13 and 14 formed on the annular casing or housing 15. This housing 15 is hollow and formed with a marginal flange 16, the latter being provided with a plurality 75 of openings 17. The casing or housing 15 is provided with a cover plate 18, likewise formed with an annular flange 19 corresponding to the flange 16 of the casing, and flange 19 is formed with openings 20, which 80 are in alignment with the openings 17 which receive suitable fastening elements.

An annular plate 21 is interposed between the cover plate 18 and the casing 15, being formed with an angularly disposed flanged 85 portion 22 which seats on the shoulder portion 23 of the casing whereby the said plate 21 is supported thereon.

Plate 21 is of any desired construction and at its central part is formed with an 90 opening, the walls of which are beveled outwardly, forming a seat 24. This opening or seat 24 registers with a relatively large opening 25 formed in the enlargement 26 of the cover plate 18. Opening 25 is interiorly 95 threaded for the threaded portion 27 of the positive contact plug 28. Plug 28 at one end is formed with a tapered portion 29 which is adapted at its enlarged portion 30 to take into the seat 24. This plug 28 is 100 formed at its central part with an opening adapted for the pin 31, which carries on its outer end a knurled head 32.

A plurality of porcelain insulating members 33 are secured to the inner surface of 105 the plate 21 by means of the screws 34.

A terminal screw 35 is mounted in the annular enlargement 36 of the cover plate 18 and a similar screw 37 is secured to the inner face of the plate 21, the purpose of 110 which will be hereinafter described.

Two resistance elements 38 and 39, com-

prising coils of wire of relatively high resistance, are attached at their opposite ends to the pin 31 of plug 28 and to screw 37. These resistance wires 38 and 39 pass around the porcelain insulating members 33.

A circuit wire 40 is appropriately connected to the outer end of plug pin 31 and a similar wire 41 is secured to the annular enlargement 36 of the cover plate 18.

- 10 These wires 40 and 41 lead from the source of electrical supply, and as the resistance elements 38 and 39 are grounded on the screw 37, and wire 41 is in electrical connection with the cover plate 18 through screw 35, a complete circuit is provided as 15 illustrated in Figure 4.

These resistance elements 38 and 39 by their novel location on the inner surface of plate 21 are disposed within the casing 15 and are in direct contact with the water to be heated and by the peculiar arrangement of the same, are in series to the lines 42 and 43, but are in parallel with each other.

- The cover plate 18 is detachably connected to the casing 14, by the bolts 44, and a hollow cap member 45 is provided with an interiorly threaded portion adapted for connection with the threaded portion of the enlargement 26 of cover plate 18. This cap member 45 is formed with a central opening 46 through which passes the lead wire 40 connected to the plug pin 31.

The electric current passes from line 42, through wire 40 and pin 31 to the resistance element 38. Likewise resistance element 39 is energized and both elements are grounded with the screw 37.

As the circuit wire 41 is connected to the screw terminal 35, the cover plate 18 by its metallic constituency and by its contacting engagement with the screw 37, the complete circuit is made.

In this manner, the resistance elements 38 and 39 are energized, and as the same are submerged in the water within the casing 45 15, they will become heated and thus in turn will heat the water. This heated water passes upwardly through pipes 12, 7 and 5 into the tank 1, and when drawn off will pass out through pipe 7. 50

Having thus fully described the invention, what I claim as new and desire to protect by Letters Patent is:—

The combination with a water tank and pipe connections therefor, of an electric heater attached to said pipe connections, and comprising a hollow casing and cover therefor, a contact plate arranged in said casing and held in position by the cover of the casing, resistance elements mounted on said plate, said resistance elements having direct contact with the water in said casing, said plate having an opening therein, the said cover having an opening therein, a plug within the opening, and connected with the resistance elements and means for attaching current conductors to the plug. 55 60 65

In witness whereof I have hereunto set
my hand.

GEORGE POMINVILLE.
